US00D540773S

(12) **United States Design Patent** (10) **Patent No.:** **US D540,773 S**
(45) **Date of Patent:** **** Apr. 17, 2007**

(54) **MOBILE PHONE**

(75) Inventors: **Song Meng**, Shenzhen (CN);
Tzu-Cheng Yu, Tu-Cheng (TW);
Hao-Ting Sun, Tu-Cheng (TW);
Jia-Ke Huang, Shenzhen (CN)

(73) Assignees: **Shenzhen FuTaiHong Precision Industrial Co., Ltd.**, Shenzhen, Guandong (CN); **Sutech Trading Limited**, Tortola (VG)

(**) Term: **14 Years**

(21) Appl. No.: **29/255,521**

(22) Filed: **Mar. 8, 2006**

(30) **Foreign Application Priority Data**

Sep. 16, 2005 (CN) 2005 3 0069797

(51) **LOC (8) Cl.** **14-03**

(52) **U.S. Cl.** **D14/138**

(58) **Field of Classification Search** D14/341-347,
D14/138, 137, 147, 218, 496; 455/575.1,
455/575.3, 575.4, 90.3, 556.1, 556.2; 379/433.01-433.13;
361/814; 348/14.02

See application file for complete search history.
